ELECTRON DISCHARGE DEVICE

John J. Glauber, West Orange, N. J., assignor to
 Federal Telephone and Radio Corporation, New
 York, N. Y., a corporation of Delaware

Application October 9, 1944, Serial No. 557,880

17 Claims. (Cl. 250—27.5)

1

This invention relates generally to electron discharge devices and particularly to the grid-cathode structures thereof.

In such devices arcing to the cathode is undesirable and is particularly deleterious where such arcing occurs to a cathode surface having a coating of emissive materials. Such coated surfaces are more susceptible to injury than uncoated surfaces since arcing tends to cause the coating to peel off or disintegrate, and to cause some of the coating materials to evaporate thereby making the electron discharge device more gassy. The additional gases or vapors thus introduced, particularly in the case of vacuum type tubes, change the mode of operation of said devices, and further tend to cause more arcing since a low-resistance arcing path is provided by the ions formed in the path of the discharge.

An object of the present invention is the provision of means for preventing or at least minimizing the possibility of arcing to the surface of an electrode structure susceptible to injury because of said arcing.

Another object of the present invention is the provision of means for preventing arcing to the coated surface of a cathode.

Certain grid structures consist of a plurality of longitudinal members arranged parallel to each other and secured together. Other forms of grid structures are comprised of a spiral wire supported by longitudinal members. In electron discharge devices employing either of such types of grid structures there is a tendency for the longitudinal members to bow at some point intermediate the ends thereof towards the cathode. The bowed portion of said members tends to vary the characteristics of the electron discharge device, makes arcing more likely, and in extreme cases may touch the cathode rendering the electron discharge device completely inoperative as well as causing damage to associated equipment. To prevent this bowing, it has heretofore been known to utilize a ring or similar element arranged around the outer sides of said longitudinal members, that is, the sides away from the cathode, and welding said ring to said sides. This proves inadequate, however, in many cases, particularly where a great deal of heat is generated inside the electron discharge device. The tendency of the longitudinal members to bow places a tension upon the welds and the heat also tends to weaken them. Consequently, the longitudinal members break away from their restraining rings, with the deleterious results heretofore mentioned.

A still further object of the present invention

2

is the provision of an improved means and arrangement for preventing bowing of said longitudinal members.

Still another object of the present invention is 5 the provision of means for preventing bowing of said longitudinal members which means also serve to prevent arcing to selected portions of the cathode.

In accordance with a feature of the present 10 invention, the inward bowing of said longitudinal members is prevented by arranging one or more metallic rings or similar elements, which are relatively incompressible, intermediate the ends of said longitudinal members and in between said 15 members, with portions of said elements abutting the inner sides of said longitudinal members and welded thereto. Consequently, when the longitudinal members tend to bow inwardly they push against said element and since said element is 20 relatively incompressible, the inward bowing is inconsequential.

Further, in accordance with a feature of my 25 invention, said elements are employed to provide a safety spark gap or arcing path to an uncoated portion of the cathode and thus to prevent injury to the cathode coating by arcing. This is accomplished by making the distance between said element and the uncoated portion of the cathode shorter than the distances between said element 30 and the coated portion of the cathode or between any portion of the grid structure and the coated portion of the cathode.

Other and further objects of the present invention will become apparent and the foregoing will 35 be best understood from the following description of embodiments of my invention, reference being had to the drawings in which:

Fig. 1 is a longitudinal sectional view of an 40 electron discharge device embodying my invention;

Fig. 2 is an enlarged detailed view of a portion 45 of the cathode-grid structure; and

Fig. 3 is an elevational view of an electron 50 discharge device partly broken away to give a view of a modified form of cathode grid structure embodying my invention.

Referring now to Fig. 1 the numeral 1 generally designates an electron discharge device having an envelope generally designated as 2 including insulating portions 3, 4 and 5, with portions 55 3 and 4 connected by an annular ring 6, and portions 4 and 5 connected by a similar annular grid ring 7. Rings 6 and 7 are provided with feather edged flanges 8 sealed to the ends of the insulating portions thereadjacent.

The envelope is completed by an anode block 9 of the reentrant type having a feather edge 10 provided at the outside thereof sealed to the lower end of insulating portion 5. The active portion of the anode is a cylindrical anode surface 11 which may be formed by boring a hole in the end of the copper block.

Arranged within said cylindrical anode surface 11 is a cylindrical cathode 12 surrounded by a cylindrical grid 13.

Passing through and sealed in the insulating portion 3 of the envelope are the heater support members 14, 15 and 16. The cathode 12 illustrated in Figs. 1 and 2 is of the indirectly heated type and supports 14, 15 and 16 are also employed as current-carrying leads for heating the heating element 17. The cylindrical coated emitter 18 of cathode 12 is supported from and electrically connected with ring 6 by means of a tubular member 19.

Grid 13 is of the type comprised of a plurality of longitudinal rods or members 20. The longitudinal rods of grid 13 are welded at one end to a flared tubular support member 21 which, in turn, is supported from grid ring 7 while at the other end said rods are welded to a spacing and supporting member 22.

As will be seen more clearly in Fig. 2, in accordance with a feature of the present invention, there is provided means for preventing the longitudinal rods 20 of grid 13 from bowing inwardly. These means consist of a plurality of relatively incompressible annular elements 23 which are arranged around the cathode, spaced therefrom and in accordance with the present invention arranged intermediate the ends of the longitudinal rods and inwardly thereof between said rods. Elements 23 are preferably made of metal and may be in the form of rings. Elements or rings 23 abut the inner surfaces or the inner sides of the longitudinal rods, that is the sides facing the cathode, and are welded to said sides at the point of contact. The elements or rings 23 are thus suspended from the longitudinal rods.

It will be seen that when the longitudinal rods 20 tend to bow inwardly, they will press against the relatively incompressible rings 23, without, however, putting tension upon the welds and consequently without tending to pull said welds apart.

Further, in accordance with a feature of this invention, means are provided for preventing arcing to the surfaces of the cathode coated with emissive materials. For this purpose, the cathode is provided with uncoated portion 24 adjacent the rings 23 supporting grid 13, these uncoated portions 24 separating coated portions 25 of said cathode. The various elements are so arranged that the distance from any ring 23 to its adjacent uncoated portion 24 is less than the distance between said ring and the nearest point of the coated portion 25. Likewise the distance between any ring 23 and the cathode 12 is less than the distance between any other point of the grid structure and the cathode structure. By the terms "grid" structure" and "cathode structure," as well as "electrode structure," I refer in this specification as well as in the claims not only to the grid, cathode, or electrode itself, but also to its leads and supports with the exception of the rings or elements 23.

Consequently it will be seen that when the potential between the cathode structure and grid structure rises to the point at which arcing is likely to occur, the arcing will occur between the

ring 23 and the uncoated portion 24 thereby preventing arcing to coated portions 25 of the cathode. It will thus be seen that rings 23 serve a dual function: to support the longitudinal rods, and to provide a safety arcing path or gap to the uncoated portions of the cathode.

While I have described my invention in connection with one form of grid and an indirectly heated type of cathode, it appears that it may 10 also be employed with other types of cathode, such as for example, the filamentary type of coated cathode, and other types of grid structure such as, for example, the spiral wire type. One form of the cathode and one form of the grid 15 specifically mentioned immediately hereinabove are illustrated in Fig. 3 wherein a tube 29 includes a cathode 27 comprised of a plurality of parallel bars, strands or filaments 28 arranged in the form of a cylinder and connected at opposite ends to rings 29 and 30 respectively which are connected to a source of filamentary heating current (not shown). The cathode 27 is surrounded by a cylindrical grid 31 comprised of a spiral grid wire 32 supported by longitudinal rods or grid laterals 33. To prevent said laterals from bowing inwardly, elements or rings 23, such as those described in Figs. 1 and 2, are arranged in relation to longitudinal rods 33 in the same manner as 20 rings 23 of Figs. 1 and 2 are arranged in relation to longitudinal rods 20. The filament bars or strands 28 of cathode 27 are provided with uncoated portions 34, and portions 35 coated with emissive materials. The distances and dimensions of the various elements are selected as 25 described in relation with Figs. 1 and 2 to provide a safety sparking gap between rings 23 and the uncoated portions 34 of the filaments 28.

Accordingly, it will be seen that my invention 30 may be employed with various types of grid-cathode structures, and while I have described above the principles of my invention in connection with specific apparatus, and particular modifications thereof, it is to be clearly understood that this description is made only by way of example and not as a limitation on the scope of my invention as set forth in the objects of my invention and the accompanying claims.

I claim:

1. An electron discharge device comprising a 35 pair of adjacent electrode structures, one of said structures having a plurality of surfaces, one of said surfaces being more susceptible to injury by arcing thereto than the other of said surfaces, and a conductive member electrically integrally connected with the surface of said other structure and spaced from said less susceptible surface a distance less than the distance between said other structure and said more susceptible surface.

2. An electron discharge device according to 40 claim 1 wherein said conductive member is separated from said less susceptible surface a distance less than the distance between said member and said more susceptible surface.

3. An electron discharge device, comprising a 45 pair of adjacent electrode structures, one of said structures having a surface susceptible to injury by arcing thereto, and a conductive member electrically integrally connected with the surface of said other structure and spaced at a shorter distance from said one structure than said other electrode to provide a shorter path between said other structure and a point on the one structure remote from said susceptible surface having less resistance to arcing than the path between said 50 other structure and said surface.

4. A discharge device according to claim 3, wherein said one structure includes a cathode having a coating of emissive material on said surface and said point is at an uncoated portion of said cathode.

5. An electron discharge device, comprising a cathode and another electrode structure adjacent said cathode structure, said cathode having a surface coated with emissive materials and an uncoated surface, and a conductive member electrically integrally connected to the surface of said electrode structure and spaced from said uncoated surface a distance less than the distance between said other electrode and said coated surface to provide a path between said electrode structure and the uncoated surface of the cathode having less resistance to arcing than the path between said electrode structure and the coated surface.

6. An electron discharge device comprising a pair of adjacent electrode structures, one of said structures having a plurality of surfaces, one of said surfaces being more susceptible to injury by arcing thereto than the other of said surfaces, and means reinforcing the other structure, and providing a shorter arcing path between said other structure and the less susceptible surface than between the other structure and the more susceptible surface.

7. An electron discharge device comprising a pair of adjacent electrode structures, one of said structures having a plurality of surfaces, one of said surfaces being more susceptible and the other of said surfaces being less susceptible to injury by arcing thereto, and means reinforcing the other structure, and providing a shorter arcing path to the less susceptible surface than to the more susceptible surface.

8. An electron discharge device, comprising a cathode having a portion of its surface coated with emissive material and an uncoated portion, a grid structure including a plurality of longitudinal members mounted around said cathode, and a relatively incompressible ring-shaped conductive element mounted around said cathode adjacent said uncoated portion, spaced therefrom, and electrically mounted directly on the surface of said members, the distance between said element and the uncoated portion being less than the distance between said longitudinal members and the coated portion.

9. An electron discharge device, comprising a cathode having a portion of its surfaces coated with emissive material and an uncoated portion, a grid surrounding said cathode, a plurality of grid laterals supporting said grid and a relatively incompressible ring-shaped conductive element mounted around said cathode adjacent said uncoated portion, spaced therefrom, and fixed to said laterals, the distance between said element and the uncoated portion being less than the distance between the grid and the cathode.

10. An electron discharge device, comprising a cathode having a portion of its surface coated with emissive material and an uncoated portion, a grid surrounding said cathode comprising a plurality of longitudinal members surrounding said cathode, and a relatively incompressible annular conductive element mounted around said cathode adjacent said uncoated portion, spaced therefrom, and fixed to said members, the distance between said element and the uncoated portion be-

ing less than the distance between the grid and the coated portion of the cathode.

11. An electron discharge device, comprising a cathode having a portion of its surface coated with emissive material and an uncoated portion, a grid structure surrounding said cathode, said grid structure including a plurality of longitudinal members mounted around said cathode, and a ring-shaped metallic ring mounted around said cathode adjacent said uncoated portion and spaced therefrom, said ring being mounted inwardly of said longitudinal members and welded to and suspended from the inner surface thereof, said ring being closer to the uncoated portion of said cathode than to the coated portions of said cathode, and also closer to the cathode than any portion of the grid is to the cathode.

12. An electron discharge device comprising a pair of electrode structures mounted one within the other, the inner structure having a plurality of surfaces, one of said surfaces being more susceptible to injury by arcing than the other of said surfaces, the other of said structures including a plurality of longitudinal members and means preventing said members from bowing inwardly, said preventing means comprising a relatively incompressible element mounted between said members intermediate the ends of the electrode structure and abutting and fixed to the inner surfaces of said members, said element being spaced from said less susceptible surface a distance less than the distance to said more susceptible surface.

13. An electron discharge device according to claim 12 wherein said element is mounted from said outer electrode structure.

14. An electron discharge device according to claim 12 wherein said element is metallic and is sealed to the inner surface of the outer electrode structure.

15. An electron discharge device according to claim 12 wherein said incompressible element is ring-shaped.

16. An electron discharge device according to claim 12 wherein said inner electrode structure is a cathode and said outer electrode structure is a grid.

17. An electron discharge device according to claim 12 wherein said outer electrode structure comprises a plurality of grid laterals and a grid wire wound around said laterals, and said incompressible element is mounted around said inner electrode structure at a distance therefrom, abutting and fixed to the inner surface of said laterals.
